UNITED STATES PATENT OFFICE

129,989

DESIGN FOR A DRESS

Ben Axelrad, New York, N. Y.

Application September 11, 1941, Serial No. 103,286

Term of patent 3½ years

To all whom it may concern:

Be it known that I, Ben Axelrad, a citizen of the United States of America, residing in New York city, county of New York and State of New York, have invented a new, original, and ornamental Design for a Dress, of which the following is a specification, reference being had to the accompanying drawing, forming part thereof.

Fig. 1 is a front view of a dress showing my new design.

Fig. 2 is a rear view thereof.

The characteristic feature of my design resides in the combination on the dress disclosed of the specific bead trim arranged as shown.

I claim:

The ornamental design for a dress, substantially as shown and described.

BEN AXELRAD.
